UNITED STATES PATENT OFFICE.

CHARLES I. E. MASTIN, OF MIDLAND PARK, NEW JERSEY.

PACKING.

Application filed August 4, 1920. Serial No. 401,145.

To all whom it may concern:

Be it known that I, CHARLES I. E. MASTIN, a citizen of the United States, residing at Midland Park, in the county of Bergen and State of New Jersey, have invented certain new and useful Improvements in Packings, of which the following is a specification.

This invention relates to packing materials, and particularly packing materials formed elongated and used for purposes where one of the packed parts moves relatively to the other, as a piston rod in its gland, and it is therefore necessary or desirable to provide the packing with means to resist wear or other undesirable results incident to such movement. My object is to provide an elongated packing of this type including coils of yielding material, which are primarily responsible for the sealing or packing quality of the packing, and other coils of less yielding material, which are adapted to resist the wear of the packing incident to friction, in which the coils shall be formed and arranged so that while the packing shall be readily capable of flexion it shall also be well adapted to withstand the wear and tear incident to relative motion between the parts packed and particularly the forces tending to disrupt or break down the materials forming the same.

In the drawing,

Figure 1 shows a piece of the elongated core;

Figure 2 shows the core having spiral coils of wear-resisting material and coils of material more yielding than that of the first coils wound spirally around the same;

Figure 3 shows the product of Figure 2 provided with a casing formed to partially surround the same while leaving exposed the coils thereof longitudinally of the article;

Figures 4 and 5 illustrate a method of manufacturing the packing, Figure 4 showing the condition of the material at two different stages in the method and Figure 5 showing one of the pieces produced by the severing operation; and

Figures 6 and 7 show, respectively, the packing pieces illustrated in Figures 3 and 5 after vulcanizing, and molded to rectangular form.

The core *a* may consist of any suitable flexible material but it is preferably a fabric sheet impregnated, coated, or otherwise

treated with rubber and then rolled up from one edge to the other in a compact mass or roll (Figure 1). A sheet is preferred for the core because it may be formed readily into the desired shape and when so formed offers uniform solidity while still being flexible.

Having such a core, I wind side by side and spirally around the same the attenuated elements *b* and *c*, the element *b* being a wear-resisting material and the other a material which is relatively yielding in nature. The wear-resisting material *b* is designed to assume the wear of and therefore be exposed to the moving one of the parts to be packed, and so it may be composed of a wire, as shown, the chief constituent of which I prefer shall be graphite because of its lubricating character. The material of the element *c*, which must be more or less yielding in character in order to obtain a good packing effect, may be a fabric or layers of fabric impregnated, coated or made to alternate with rubber. If element *c* is of such material and it is arranged, as shown, so that its edges stand presented to the coils *b*, it is well adapted to yield to the latter in the flexing of the packing.

If the packing element thus formed contains rubber, as above set forth, and as is preferred, it will be best to vulcanize as the final step in its manufacture, and in vulcanizing it may be molded to some suitable form other than circular in cross section, as square in cross section. The coils *c* which are relatively yielding serve in the stuffing box or equivalent to seal the joint between the parts to be packed, while the other coils *b* act to resist the wearing away of the packing. The coils *b* being in the best form of non-yielding material (as the wire mentioned), so that while they respond to attrition they will not respond to other lateral displacement of their molecules, any kneading produced in the packing as the result of the rubbing thereof by one of the packed parts is localized, or less effective on the rubbed surface as a whole than on each individual coil *c*, whereby the surface exposed to such part has a more enduring capacity than if it were composed throughout of more or less yielding material. Where the coils *b* are not only formed of wire but are lubricating in nature, so that any grip incident to rubbing is thereby greatly reduced, they protect the packing from the

100

110

effects of the rubbing and reduce the intensity thereof, so that there is not only less frictional wear but less tendency to disrupt and disintegrate the materials of the packing.

Figure 3 shows the product of Figure 2 contained in a casing *d* which partially surrounds the structure including the core *a* and spiral windings *b* and *c*, leaving the windings exposed longitudinally of the product. The casing *d* may be formed of a fabric or layers of fabric impregnated, coated or made to alternate with rubber. The casing adheres to the core because of the presence of rubber as a constituent of the casing and of the element *c*; it may be made to adhere in any other way. Rubber being present in the article thus produced, the same may be vulcanized and in the process of vulcanizing be molded to any suitable shape, for instance that shown in Figure 6. The acting face of the packing, that is the face which is presented to the moving part to be packed, is that face where the spiral windings will be exposed, as illustrated in Figure 6.

I may take a plurality of flexible cores *e*, for instance like the core *a*, and form a covering around and adhering to them, as by spirally wrapping around them and side by side attenuated pieces *f* and *g* respectively similar to the pieces *b* and *c* already described and then wrapping a sheet of suitable material, as fabric *h* impregnated, coated or otherwise treated with rubber, around the spiral windings. On cutting the article thus produced in a plane indicated by 5—5 in Figure 4, i. e., between the two cores, two packing members will result; and the casing of each (to wit, the half of the fabric coating *h* appertaining to each) of these will expose at one side and longitudinally the wear-resisting material, but in section (which in fact is ultimately the condition which the coils of the element *b* assume when they become worn away in the gland). Usually the two parts resulting after the severing will be vulcanized, and in the vul-

canizing treatment they may be molded into any form as that shown in Figure 7.

It will be best to subject the packing, in whatever form or by whatever method it is made, to pressure, as in the mold when vulcanizing it, in order to compress the constituent parts into a compact mass and so insure integrity and stability of structure. It will be understood that the result of this treatment in the case of the packing shown in Figure 5 will be to close up the channels existing at *i* between the core and the marginal portions of the casing—see Figure 7.

Having thus fully described my invention, what I claim as new and desire to secure by Letters Patent is:

1. A flexible unitary packing body including coils arranged around a common axis side by side, the alternating coils being composed of unyielding material and the remaining coils of yielding material.

2. A flexible elongated packing body including coils arranged around a common axis and side by side, the alternating coils being composed of wear-resisting lubricating wire and the remaining coils of material more yielding than that of the first-named coils.

3. A flexible elongated packing body including coils arranged around a common axis and side by side, and a flexible core on which said coils are wound consisting of a rolled-up sheet of yielding material.

4. A flexible elongated packing body including coils arranged around a common axis and side by side, the alternating coils being composed of yielding sheet material and the remaining coils of less yielding material, the edges of said sheet material being presented to the latter coils.

5. A flexible elongated packing body including coils arranged around a common axis and side by side, and a casing of yielding material adhering to said coils and exposing the same exteriorly thereof longitudinally of said axis.

In testimony whereof I affix my signature.
CHARLES I. E. MASTIN.
